United States Patent Office

Des. 191,599
Patented Oct. 17, 1961

191,599

BOTTLE

Percy Russell King, Leaside, Ontario, Canada, assignor
to Javex Company Limited, Montreal, Quebec, Canada

Filed Aug. 15, 1960, Ser. No. 61,753

Term of patent 14 years

(Cl. D58—8)

The figure is a side elevational view of a bottle, showing my new design.

The bottle is cylindrical in cross-section throughout and the side not shown is the same as the side shown.

I claim:

The ornamental design for a bottle, as shown and described.
